CLAIM

The ornamental design for a lamp device with fan element, as shown and described.

DESCRIPTION

FIG. 1 is a schematic perspective view of lamp device with fan element showing my new design;

FIG. 2 is an another schematic perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The dash lines presented in the drawings depict portions of the lamp device with fan element in which the design is embodied that form no part of the claimed design.
